(57) **CLAIM**

The ornamental design for a combined beverage and food container, as shown and described.

DESCRIPTION

FIG. 1 is a top perspective view of a combined beverage and food container showing my new design.

FIG. 2 is a bottom perspective view thereof.

FIG. 3 is a front elevational view thereof.

FIG. 4 is a right side elevational view thereof.

FIG. 5 is a rear elevational view thereof.

FIG. 6 is a left side elevational view thereof.

FIG. 7 is a top plan view thereof.

FIG. 8 is a bottom plan view thereof.

FIG. 9 is a top perspective view of a second embodiment thereof.

FIG. 10 is a bottom perspective view thereof.

FIG. 11 is a front elevational view thereof.

FIG. 12 is a right side elevational view thereof.

FIG. 13 is a rear elevational view thereof.

FIG. 14 is a left side elevational view thereof.

FIG. 15 is a top plan view thereof; and,

FIG. 16 is a bottom plan view thereof.

The broken line showing in the figure drawings are included for the purpose of illustration and form no part of the claimed design.
